UNITED STATES PATENT OFFICE.

CHARLES E. DILLON AND LEE SAVAGE, OF SPRINGFIELD, MISSOURI.

LADDER.

1,028,004.

Specification of Letters Patent.

Patented May 28, 1912.

Application filed March 7, 1911. Serial No. 612,802.

To all whom it may concern:

Be it known that we, CHARLES E. DILLON and LEE SAVAGE, citizens of the United States, residing at Springfield, in the county 5 of Greene and State of Missouri, have invented certain new and useful Improvements in Ladders, of which the following is a specification.

This invention relates to improvements in 10 ladders, more particularly to the class of step-ladders, and has for one of its objects to provide a simply constructed ladder whereby the steps are firmly united to the side members without cutting into either the 15 steps or the side members, or otherwise reducing or weakening them.

Another object of the invention is to provide a device of this character whereby the steps and sides of a ladder may be quickly 20 and firmly united without the necessity for forming tenons or mortises, or the like, in the parts.

With these and other objects in view the invention consists in certain novel features 25 of construction as hereinafter shown and described and then specifically pointed out in the claim, and in the drawings illustrative of the preferred embodiment of the invention, Figure 1 is a perspective view of a portion 30 of a step-ladder constructed in accordance with the improved device; Fig. 2 is a front elevation of a portion of one of the steps and a portion of one of the side members of a ladder, with the improvement applied; Fig. 3 is a perspective view of one of 35 the attachments detached, viewed from the inner side; and Fig. 4 is a view similar to Fig. 3, viewed from the outside.

Corresponding and like parts are referred 40 to in the following description and indicated in all the views of the accompanying drawings by the same reference characters.

The improved device may be applied to 45 ladders having side members and steps of various sizes and forms, but is designed more particularly for use in the construction of step-ladders having flat side members and steps, and for the purpose of illustration is shown thus applied, and in the 50 drawings the side members are represented conventionally at 10 and the steps at 11. The steps are usually connected at an angle to the longitudinal plane of the sides, so that when the step-ladder is in use with 55 the sides inclined, the upper surfaces of the steps will be level or horizontal.

The improved device consists of a device whereby the steps 11 are united firmly to the sides 10 without cutting either the steps or the side members, and is preferably constructed from sheet or plate steel pressed into the required shape. Each of the connecting devices consists of a horizontal body portion 12 having right angled ends 13-14 and with the terminals of the ends bent at 60 right angles thereto, as shown at 15-16, and extended for a short distance in parallel relation to the body 12, as shown. The distance between the terminals 15-16 and the body 12 corresponds to the thickness of 70 the side members 10, while the distance between the portions 13-14 corresponds to the width of the member 10. The member 12 is extended upwardly above the line of the end portions 13-14, as represented at 75 17, and preferably reduced, as shown, to decrease the weight. The body 12 is provided with a plurality of screw receiving apertures, as represented at 18, while the terminals 13-14 are likewise provided with 80 screw receiving apertures 19-20. Extending from the body 12 at its lower edge is an integral flange 21 having screw receiving apertures 22.

The body portion 12 is designed to bear 85 against the inner face of the side 10, while the terminals 13-14 bear over the edges of the side member with the terminals 15-16 bent around the outer corners, as shown in Fig. 1. The supporting device is then secured to the side members 10 by screws inserted through the various apertures 18-19 and the steps 11 supported upon the ledges or flanges 21 and secured by screws inserted through the apertures 22. By this means 90 the steps and side members are firmly united and supported and without the necessity for cutting either the steps or side members. In practice the terminals 15-16 of the ends 13-14 will be bent around the 100 outer corners of the sides 10 by any suitable implement after the supporting device has been applied and the screws inserted, this bending of the parts causing same to be partly embedded in the relatively soft wood 105 of the sides and thus materially increase the grip of the supporting device thereon.

The supporting devices will preferably be made rights and lefts, but will otherwise be duplicates at the opposite ends of the steps. 110 In practice the steps 11 will be provided with the supporting devices having the ter-

minals 15—16 unbent or extending at right angles to the end portions 13—14, and shipped, together with the sides 10, in knocked-down shape, and then assembled 5 where the ladder is to be sold. When thus assembled it will be obvious that it is only necessary for the operator to place the steps at the required positions upon the sides, apply the screws through the apertures 10 19—20 and then bend the terminals 15—16 around the sides 10 by the blow of a hammer or other implement. Thus the device is readily adapted to sides of various thicknesses without structural change in the 15 device.

The improved device is simple in construction, can be inexpensively manufactured, and applied without material structural change to step-ladders of various sizes 20 and forms.

Having thus described the invention, what is claimed as new is:

25 A step ladder including side members and steps, and supporting devices each consisting of a vertically disposed body portion abutting against the end of a step and ex-

tending thereabove and provided with right angled portions extending over the opposite edges of the side member and bent around and engaging the outer face thereof, said 30 body portion having a lateral flange extending underneath the step for engagement with the lower face thereof, the vertical body portion being formed above the step with an aperture to receive a fastening device and below the upper face of the step with corresponding apertures, whereby the fastening devices in said last named apertures will be covered by the end of the step and thereby prevented from coming out, 35 fastening devices extending through the flange into the step, and other fastening devices extending through the right angled portions into the side members.

In testimony whereof, we affix our signatures in presence of two witnesses.

CHARLES E. DILLON. [L. S.]
LEE SAVAGE.
